UNITED STATES PATENT OFFICE.

MICHAEL BARRY LEONARD, OF RICHMOND, VIRGINIA.

ELECTRICAL APPARATUS FOR CONTROLLING SIGNALS.

SPECIFICATION forming part of Letters Patent No. 517,419, dated March 27, 1894.

Application filed June 17, 1893. Serial No. 477,959. (No model.)

To all whom it may concern:

Be it known that I, MICHAEL BARRY LEONARD, a citizen of the United States, residing at Richmond, in the county of Henrico and State 5 of Virginia, have invented certain new and useful Improvements in Electrical Apparatus for Controlling Signals; and I do hereby declare the following to be a full, clear, and exact description of the invention, such as will 10 enable others skilled in the art to which it pertains to make and use the same.

My invention relates to improvements in interlocking block signaling apparatus such as are ordinarily employed in signaling along 15 a line of railway between two or more offices or stations, and especially designed for use in controlling semaphore or other visual signals.

The primary object of the invention is to 20 provide simple, efficient and inexpensive means for controlling the signals between two or more stations, so as to require the concerted action of the two operators at two proximate stations to permit a train to enter 25 the block, thereby lessening the liability to accidents by reason of carelessness or negligence upon the part of individual operators in working the signals.

A further object is to dispense with the use 30 of selecting or preparing instruments in controlling the signals, and to provide simple and efficient electro-mechanical means for producing the desired results without the intervention of complex and expensive mechanism such as is ordinarily employed in this 35 class of inventions.

The invention will first be described in connection with the accompanying drawings which form a part of this specification, and 40 then pointed out in the claims at the end of this description.

Referring to the drawings by letters of reference, Figure 1 is a diagrammatical representation, partly in perspective and partly in 45 side elevation, of an interlocking block signaling system between two block offices or stations, embodying my invention. Fig. 2 represents a perspective view of the signal locking mechanism and unlocking magnet 50 with inclosing casing partly broken away. Fig. 3 is a horizontal section through the inclosing casing of the unlocking magnet, and

Fig. 4 is a side elevation illustrating the application of an electric motor for automatically actuating the signal. 55

A and B may denote two proximate block offices or stations located along the line of a railway, and each provided with a signal, signal locking mechanism and unlocking magnet constructed and adapted to operate alike. 60 The main line wire W, is normally connected through the unlocking magnets M, M, at the respective stations A and B, to ground, by means of the wires a, a'; a switch S, being interposed between the magnet and ground connection, as shown, for the purpose of permitting the ground connection to be readily transferred from the magnet to a normally open local battery, and thus cause an impulse or current to pass from either station over the line 65 and thence to the magnet at the distant station, so as to energize the magnet at the latter station and cause the same to raise its armature and release the signal, and at the same time open the circuit between the magnet and the ground at the home station, so as to prevent the home magnet from being energized by the home battery and thereby release the 70 home signal. The wire a, may extend from the wiring of the magnet M, to a contact strip 75 or slip s, opposite which is placed a similar contact strip s', from which the wire a', extends to ground. A third contact strip or slip s², is connected by means of a wire a², through a battery M. B. to the main line wire, so that 80 when the switch S, is shifted so as to close the circuit through said battery, the magnet will be cut out and current may flow over the line 85 to the distant station, through the distant magnet, and thence to ground without affecting the home magnet. An oscillating contact strip or key t, may be fitted upon a rotatable rod T, having a handle T', accessible 90 to the operator at the home station, for the purpose of partially rotating the rod so as to transfer the grounded circuit to the battery and cut out the home magnet by disconnecting the plates s, s', and connecting the 95 plates s², s².

The signal may consist of the usual counterweighted semaphore blade or arm C, connected by means of rods c, c', and an intermediate bell-crank lever c², or other suitable connection, with one arm of the operating le-

ver L, the opposite arm of which may be connected to a notched lever-bar L', by means of a pivoted link l. The lever-bar L', has a notch l', in the upper edge thereof, which, in the normal position of the semaphore blade, is adapted to be engaged by the depending end of the pawl-like armature m, of the electro-magnet M, when the latter is de-energized, so as to retain and lock the signal in its normal position. In the normal position of the signal, an elongated opening or slot l², on the under side of the notched lever-bar L', is so arranged with respect to a pin or projection t', upon the rod T, that the latter may be rotated by allowing the pin to enter said opening or slot for the purpose of shifting the switch, but in any other position of the notched lever-bar said pin will not register with the slot l², and the rod cannot be rotated so as to break the ground connection with the main circuit. But when the magnet is energized and its armature m, raised, the latter will be disengaged from the notch l', in the lever-bar L', and permit the signal operating lever to be actuated for the purpose of shifting the signal from its normal position to "caution," "safety," or such other position as may be determined.

An enunciator device or electric bell D, may be placed in a local battery circuit d, d', for the purpose of notifying the local operator when his semaphore lever is unlocked. This latter circuit is normally open and is adapted to be closed by the local points d², d³, when the armature-lever m, is raised. The signal may be shifted by hand power applied to the hand lever L, Fig. 1, or automatically, as illustrated in Fig. 4, wherein I have illustrated an electro-motor N, whose armature-shaft is adapted to impart motion to accelerating gearing O, the larger gear-wheel o, of which is fixed to a drum shaft O', from which a cord may extend to one arm of the signal lever, so that when the motor circuit is closed and the lever unlocked, the signal may be automatically shifted by the motor and placed either in normal, or any desired position, without requiring the presence of a local operator. The motor N, may be placed in a normally open local battery circuit, n (or the above-mentioned bell circuit) the local points n', n², of which are adapted to be closed when the armature m, of the magnet M, is raised and the notched lever-bar unlocked, thereby causing the motor to automatically shift the signal. As the semaphore lever approaches the limit of its movement in reversing the signal the motor may be automatically thrown out of gear by an ordinary clutch device, or its movement may be stopped by automatically breaking the motor circuit. This may be accomplished by means of local circuit connections n³, terminating in normally closed spring contacts n', adapted to be separated so as to open the circuit at the proper time by means of a wedge P, of wood or vulcanized fiber secured to the

lever. Two points are thus provided in the motor circuit, whereby it is adapted to be automatically broken as the lever reaches the end of its stroke in either direction. When the local points at the armature are open the signal lever will be locked in normal position, but such points will be closed the moment the signal is unlocked, and thereupon the motor will operate to reverse the signal. When the lever has been pulled forward by the motor and the signal reversed the separation of the spring contacts will open the motor circuit and the motor will stop. In drawing back the signal operating lever to restore the signal to normal position the armature of the motor will be permitted to revolve as an idler, allowing the cord or rope connecting the lever with the drum of the motor gearing to be unwound.

It is designed in practice to use but one set of local connections on the armature, for the reason that when the motor is used the bell will not be necessary to notify the operator when the lever is unlocked; the motor being adapted to reverse the signal. But two sets of local connections on the armature may be employed simultaneously should it be desirable to use both the bell and the motor.

The operation of the invention will be readily understood from the foregoing description taken in connection with the accompanying drawings. The main line wire being normally connected through both unlocking magnets 100 to ground, while the battery at each office or station is in an open circuit;—when the signal key or switch S, at either station, is turned, it will disconnect the ground from the line and magnet wire, and connect the ground to the battery, thus throwing the latter into the main circuit and allowing a current to flow over the line to the opposite station and thence to ground through the magnet at the latter station; provided the signal and switch 110 at the latter station are in proper position. The latter magnet being thus energized will attract its armature and release the notched lever-bar L', so as to permit the operator, or the automatic mechanism, to shift the signal. 115 The connection between the ground wire and the magnet wire at the proximate or home station being then open, no current can flow through the magnet at that station, and consequently it will not be affected. For example, the signal or semaphore at station A, being locked in the danger, or "stop" position by the armature m, of the magnet M, which magnet is normally unenergized;—to change the position of the signal from stop to "clear," 125 at station B, the operator at the latter station instructs the operator at station A (by means of an ordinary Morse telegraph or over a telephone line) to unlock his (B's) signal. The operator at station A, provided the track is 130 clear in the block between him and station B, will then turn his signal key a partial revolution, and in so doing will connect the battery at that station to ground and thereby

cause a current to flow over the main line wire to the unlocking magnet at station B, energizing the magnet at the latter station and causing it to raise its armature, and at the same time closing the local bell circuit (in case the latter is used) so as to cause the bell to ring and notify the operator that his signal is unlocked and can be thrown to the clear position; or, if the motor circuit only is used, closing the latter so as to cause the motor to automatically shift the signal. But before the operator at station A, can turn his signal key to establish the desired electrical connection with the distant station he must first place his own signal in its normal position, which in the present case is the "danger" or "stop" position. This must be done in order to permit the pin or projection t' , on the key rod or shaft T, to pass into or through the slot t^2 , on the under side of the locking bar L'. Otherwise, the signal key will not be permitted to turn and the contacts cannot be made so as to energize the distant magnet. To unlock the signal at station A, the above operation is simply reversed. In either case the operator at the proximate or home station must place his own signal in normal position before he can establish electrical connection with the distant station so as to unlock the distant signal, and having placed his own signal at danger, or in the desired normal position, it will be locked in such position by the armature of his magnet, which is normally unenergized and can be affected by a current transmitted from the distant station only.

Instead of the notched lever-bar for locking the semaphore lever, a rotary notched disk or other equivalent means may be used for this purpose, and make-and-break devices or switches of other forms than those herein shown may be employed, without departing from the spirit of my invention, and hence I do not desire to be limited to the exact construction and arrangement of parts shown and described.

Having thus fully described my invention, what I claim as new, and desire to secure by Letters Patent of the United States, is—

1. An interlocking block signaling system comprising a normally grounded electric wire connecting two or more offices or stations, a visual signal, locking mechanism therefor, and an unlocking magnet at each station; said magnets being connected by said normally grounded wire and having their armatures arranged to lock and retain said signals in normal position, a local battery at each station, and means adapted to throw said battery into the main line through the distant magnet without affecting the home magnet so as to release the distant signal only, but not adapted to operate until the home signal is placed in normal position, substantially as described.

2. An electrical apparatus adapted for railroad block systems for signaling between two or more offices or stations, comprising at each

station a visual signal, mechanism for locking the signal in normal position, a local battery, an unlocking magnet adapted to operate upon said locking mechanism and release the signal; said unlocking magnet being connected by a normally grounded main wire, and contact devices arranged in relation to the signal mechanism so as to operate only when such mechanism is placed in normal position, to cut out the magnet at the home station and simultaneously throw the local battery into the main line, whereby the signal at either station is adapted to be unlocked solely by the operator at the distant station and then only when the signal at the latter station is locked in normal position, substantially as described.

3. In an interlocking block signaling system comprising two or more offices or stations, a visual signal for each station, mechanism for locking the signals in normal position, and means for releasing the signal from a distant office, comprising a normally grounded main wire including an unlocking magnet for each signal, and a contact device or switch adapted to throw the local battery into the main line through the distant magnet so as to cause the latter to release the distant signal without affecting the home signal, and means for preventing this operation until the signal at the station where the switch is to be worked is placed in normal position, whereby the signal at each station may be unlocked by the operator at the distant station and then only after the latter operator has placed his own signal in normal position, substantially as described.

4. In a signaling system between two or more offices or stations, a visual signal at each station and means for locking the same in normal position, comprising a notched lever-bar connected with a signal operating lever and an armature-lever adapted to engage a notch in said bar and lock the signal mechanism, together with an electro-magnet adapted to actuate said armature-lever and release the signal, a local battery at each station, a normally grounded wire with which the magnets are connected, and a contact device or switch for throwing the local battery into the main line so as to energize the distant magnet only and unlock the distant signal; said contact device being adapted to operate only when the signal at the home station is placed in normal position, substantially as described.

5. In a signaling system between two or more stations, a visual signal at each station, and means for locking the same in normal position, unlocking magnets, a normally grounded wire extending between the stations and including said magnets, a local battery at each station, and means for transferring the ground connection to either of said local batteries so as to include the distant unlocking magnet and release the distant signal, and an electric motor adapted to automatically shift the signal when released, substantially as described.

6. In a signaling system between two or more stations, a visual signal at each station,

mechanism for locking the signal in normal position, means for automatically shifting the signal when said mechanism is unlocked, an electro-magnet whose armature is adapted to 5 lock the signal, a normally grounded wire including said magnet, a local battery, and a device for cutting out the magnet at the home station and simultaneously throwing the local battery into the main line through the distant 10 magnet so as to unlock the distant signal; said device being adapted to operate only when the home signal is placed in normal position, substantially as described.

7. In a signaling system, a visual signal and 15 means for locking the same in normal position, comprising a sliding notched lever-bar connected with the signal operating lever, an armature-lever adapted to engage a notch in said bar so as to lock the signal operating 20 mechanism, an electro-magnet adapted to actuate said armature-lever and release the signal, a local battery, a normally grounded wire including said magnet, and contact devices for throwing said local battery into the main 25 line so as to include the distant magnet and unlock the distant signal; said contact devices consisting of a rotatable shaft carrying a movable contact plate and provided with a pin or projection adapted to operate only when said 30 pin registers with a slot in the notched lever-bar with the signal at the home station in normal position, substantially as described.

8. In a signaling system, a visual signal, means for locking the same in normal position, and an unlocking magnet at each of two 35 or more stations, a normally grounded wire extending between the stations and including said magnets, a local battery at each station, and means for throwing said local batteries into the main line so as to include a 40 distant unlocking magnet and release a distant signal, and a signal bell controlled by the armature of the unlocking magnet, substantially as described.

9. In combination with the signal, the unlocking magnet, whose armature is adapted to normally lock the signal, an electric circuit in which said magnet is placed, a local circuit having an electric motor placed therein and adapted to reverse the signal, normally open 50 contact points in said local circuit adapted to be closed by the unlocking armature in releasing the signal, and normally closed contact points in the same circuit and means for opening the same when the signal is reversed, 55 substantially as described.

In testimony whereof I affix my signature in presence of two witnesses.

MICHAEL BARRY LEONARD.
